J. KULCZYCKI

CURTAIN SUPPORTING ATTACHMENT FOR WINDOW FRAMES

Filed Jan. 19, 1922

FIG. 2.

Inventor
J. Kulczycki

By *R. Morgan Elliott & Co.*

Attorney

UNITED STATES PATENT OFFICE.

JOSEPH KULCZYCKI, OF CHICAGO, ILLINOIS.

CURTAIN-SUPPORTING ATTACHMENT FOR WINDOW FRAMES.

Application filed January 19, 1922. Serial No. 530,414.

To all whom it may concern:

Be it known that I, JOSEPH KULCZYCKI, a citizen of the United States of America, residing at Chicago, in the county of Cook 5 and State of Illinois, have invented certain new and useful Improvements in Curtain-Supporting Attachments for Window Frames, of which the following is a specification.

10 My invention relates to certain new and useful improvements in curtain supporting attachments for window frames.

The primary object of my invention is to provide a curtain supporting frame which 15 is detachably mounted in the head casing of the window frame.

With the above general objects in view and others that will appear as the nature of the invention is better understood, the same 20 consists of the novel form, combination and arrangement of parts hereinafter more fully described, shown in the accompanying drawing and claimed.

In the drawing, wherein like reference 25 characters designate corresponding parts throughout the several views,

Figure 1 is a front elevational view of my device partly in section and partly broken away and upon the line II—II of Fig. 2,

30 Figure 2 is a top plan view of Fig. 1 showing the same partly broken away,

Figure 3 is a vertical sectional view upon the line III—III of Fig. 1,

Referring more in detail to Figs. 1 to 3, 35 my invention consists of the usual type of window frame 1 and head casing 2. Running longitudinally therewith and spaced inwardly of the ends thereof is a socket 3 in the upper surface of the head casing 2.

40 Detachably positioned upon the head casing is a curtain supporting frame of substantially U-shape in plan and including end

members 4 and a similar ornamental front member 5 with their ends rigidly connected together. The rear ends of the members 4 45 are connected by a metallic strip 6 which is suitably fastened at its ends upon the upper surfaces of the said end members 4 by screws 7 or the like. A mounting block or strip 8 is fastened by screws 9 to the under surface of the metallic strip 6 and is of such dimensions as to snugly fit in the socket 3 of the head casing 2. Permanently carried by the inner faces of the end members 4 are curtain pole supporting brackets 10 having 50 a curtain pole 11, carrying the usual type of curtain 12, supported therein.

From the foregoing description it is believed that the construction and operation as well as the advantages of the present invention will be readily understood and appreciated by those skilled in the art. 60

Minor changes may be made in the invention without departing from the spirit and scope thereof. 65

What is claimed as new is:—

In combination with a window frame including a head casing provided with an open top socket spaced inwardly of the ends of said head casing, a curtain supporting frame 70 substantially U-shaped in plan and including end members arranged with their free ends disposed to abut a wall surrounding said frame, a metallic strip having its ends fastened upon the upper surface of said end members and rigidly connecting the latter members, a block carried by the under surface of said strip adapted to be received within the socket of the said casing head, and curtain pole supporting brackets upon 75 the said curtain supporting frame. 80

In testimony whereof I affix my signature.

JOSEPH KULCZYCKI.
